UNITED STATES PATENT OFFICE.

EDWARD F. STEPHENS, OF AUSTIN, NEVADA.

CAR-COUPING.

SPECIFICATION forming part of Letters Patent No. 417,522, dated December 17, 1889.

Application filed September 26, 1889. Serial No. 325,138. (No model.)

To all whom it may concern:

Be it known that I, EDWARD F. STEPHENS, a citizen of the United States of America, residing at Austin, in the county of Lander and State of Nevada, have invented certain new and useful Improvements in Automatic Car-Couplings; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My invention relates to certain new and useful improvements in automatic car-couplings of that class generally termed "twin jaw," in which two identical jaws are used, so that when brought together they will interlock to connect the cars; and my invention consists in a car-coupling provided with pivoted twin jaws which move horizontally or laterally upon their pivots, the jaws each being pivoted to a sliding block which moves within the draw-head or bumper, and are actuated in one direction by springs, as will be hereinafter described.

My invention further consists in providing each of the coupling-jaws with an arm, one end of which slides in recesses formed in the jaw, while the other end is connected to a lever, the operation of which in one direction will uncouple the cars, its movement in the opposite direction being controlled by an interposed spring, as will be hereinafter fully set forth, and particularly pointed out in the claims.

In the accompanying drawings, Figure 1 is a bottom plan view; Fig. 2, an end view. Fig. 3 is a sectional view on the line $x-x$ of Fig. 2, and Fig. 4 is a perspective view of one of the jaws and sliding block detached.

A refers to a casting or bumper, which is attached in any suitable manner to the car body or frame; and it consists of a horizontal top wall or plate a , from which depend vertical walls b , having formed thereon lugs c , which are perforated for securing the bottom plate d and other parts rigidly to the car-body. To the forward ends of the side walls are formed inwardly-projecting flanges b' , which limit the forward movement of

the sliding block located within the bumper. The rear portion of the casting A is contracted and extended rearwardly, and from the same depend flanges f , which act as guides for a draw-bar D, the forward end of which is rigidly attached to a sliding block B, carrying the pivoted jaw. The bottom plate d of the casting serves to hold in place the sliding block B, which has on each side lateral projections h , which slide against the walls b , their front faces abutting against the flanges b' to limit the forward movement of the block, while excessive rear movement is prevented by the rear faces of the lugs contacting with the flanges f . The block B has a rearward extension i , to which is bolted the draw-bar D, and this extension is provided with an opening or slot in which a lever may be pivoted, which lever forms a part of an automatic brake, for which an application for patent has been filed on even date herewith.

On the forward end of the block B are formed ears k , and behind the same is formed a deep-seated recess l , within which lies the rear end of the coupling-jaw, as well as a spring m , one end of which bears against the side of the recess while the other bears against a projection formed on the rear end of the jaw. The coupling-jaw E is made of a single piece, and is pivoted to the sliding block B, between the lugs k , the construction of the jaw being shown fully in Fig. 4, and it will be observed that shoulders are formed upon the jaw, which lie snugly against the front and side faces of the lugs. One side of the jaw is perfectly straight, while the opposite side is at an angle therewith and is provided with a notch E' , which permits the jaws to interlock. In the straight side and in the bottom of the coupling-jaw are formed longitudinal grooves o , with which engage a casting O, having at its lower part a horizontal projection p , from which an upwardly-projecting pin p' extends, which enters the groove o , while the upper horizontal portion p^2 enters the groove o' in the side of the coupling-jaw. A vertical pin passes through the members p and p^2 of the casting and has placed thereon an anti-friction roller which contacts with the straight side of the coupling-jaw. By this construction the coupling-jaw is not only allowed a longitudinal slid-

ing movement, but also a pivotal movement in the casting O. To the vertical portion of the casting O is secured a horizontal pin o², which passes through a suitable support attached to the car, between which and the casting a spiral spring may be interposed, which will also tend to throw the jaws together and hold them interlocked. To the end of the pin is attached a chain, as shown, which is also secured to the short end of an uncoupling-lever J, pivoted to the car, and the upper portion of this lever passes through a guide having ratchet-teeth with which a rigid pawl on the lever engages to hold the coupling-jaws out of engagement when desired. It will be noted that the pin and casting O not only serve to uncouple the jaws, but also assist in sustaining the jaws in a horizontal position. It will also be noted that the coupling-jaws are of such a length that they will enter the adjacent castings A A, and thus also assist in supporting the coupling-jaws when the cars are coupled.

The device described is entirely automatic in action, and though it is especially designed to be used in connection with my automatic brake it is evident that it can be employed independently thereof, or with other styles of automatic brakes.

Having thus described my invention, what I claim as new, and desire to secure by Letters Patent, is—

1. In an automatic car-coupling, the combination, with the castings or bumpers A A, of blocks B, adapted to slide therein, said blocks being provided with lateral extensions which abut against stops formed on the bumpers, draw-bars connected to the sliding blocks, and twin spring-actuated and notched coupling-jaws pivoted to the forward end of the sliding blocks, substantially as shown, and for the purpose set forth.

2. The combination, in a car-coupling, of a bumper or casting supporting a sliding block to which the draw-bar and pivoted coupling-jaw is attached, said coupling-jaw having longitudinal grooves with which a casting

connected to the uncoupling mechanism, as shown, engages, substantially as and for the purpose set forth.

3. The combination, in an automatic car-coupling, of a bumper inclosing a sliding block, said block having a recess within which is located a spring, a notched coupling-jaw pivoted near its rear end to the sliding block and provided with a rearwardly-extended portion or lug with which the spring engages, and an uncoupling mechanism, as shown, upon which the coupling-jaw slides, substantially as set forth.

4. In a car-coupling, the combination of a bumper or casting A, having stops b' and flanges f formed thereon, a retaining-plate d, attached to said casting, a block B, adapted to slide longitudinally within the bumper, said block having lateral projections which engage with the stops and ends of the flanges, a rearward extension to which the draw-bar is attached, and a recessed front portion containing a spring in front of which the coupling-jaw is pivoted, said coupling having a notch E' and grooves o o', with which a pin and one end of a casting carried by the uncoupling mechanism engage, substantially as shown, and for the purpose set forth.

5. The combination, in an automatic car-coupler constructed substantially as shown and provided with coupling-jaws having longitudinal grooves, of a casting having a horizontal portion which enters one of the grooves, and a pin extending from the lower portion of the casting to enter the other groove, an anti-friction roller which abuts against the straight side of the coupling-jaw, a horizontal pin attached to the casting, a support, and means, as shown, for operating the same, substantially as set forth.

In testimony whereof I affix my signature in presence of two witnesses.

EDWARD F. STEPHENS.
